UNITED STATES PATENT OFFICE

CALVIN M. BOLSTER, OF LAKEHURST, NEW JERSEY

PUMP

Application filed December 23, 1927. Serial No. 242,079.

This invention relates to rotary pumps, compressors or similar devices, and has for one of its objects the provision of an improved device of this character which will be relatively inexpensive to manufacture, and highly efficient in its operation.

Further objects and various features of novelty will be apparent from the following description and accompanying illustration 10 of a specific embodiment which for convenience and simplicity will be referred to as a pump. In the drawings:

Fig. 1 is an end elevation of the pump taken from the left of Fig. 2;

15 Fig. 2 is a side elevation taken from the right of Fig. 1;

Fig. 3 is an end elevation taken substantially on the line 3—3 of Fig. 4 with the head removed;

20 Fig. 4 is a central vertical longitudinal section taken on the line 4—4 of Figs. 1 and 6;

Fig. 5 is an end elevation taken substantially on the line 5—5 of Fig. 4 with the casing head and rotor end plate removed;

25 Fig. 6 is a central vertical transverse section taken on line 6—6 of Figs. 2 and 4; and

Figs. 7 to 10 are diagrammatic views taken at different periods in the operation.

30 By reference to the drawings it will be observed that the apparatus comprises a casing A including an intermediate or body portion 12 and spaced heads 13 and 14 secured to the ends of the intermediate section by

35 screws 15 or equivalent devices. The intermediate portion of the casing is provided with a cylindrical pressure chamber 16 into which open an inlet passage 17 and an outlet

40 passage 18, each of which passages terminates in a narrow slit-like longitudinal port 19 at its inner end and is provided with a coupling nipple 20 at its outer end for attachment of suitable pipes for conducting fluid into and out of the pressure chamber of the pump.

45 Each of the heads 13 and 14 is provided with shaft bearings 22 axially concentric with the cylindrical pressure chamber for the reception of a rotor shaft. The bearing bore for the head 14 extends entirely through the head, including an annular projection 23.

The projection is counterbored from its outer end to furnish an annular packing space and is externally threaded to receive a packing retaining nut 24.

According to this invention means is provided within the cylindrical pressure chamber to form with the walls thereof, a working space for handling the fluid and also for forcing the fluid between the inlet and outlet.

Various forms of devices may be employed for this purpose but the form which is preferred and which will be particularly described by way of example herein consists of a rotor B including a shaft 30, and a piston

31 preferably formed integral with the shaft. The shaft ends operate within the bearings 22 provided therefor in the heads 13 and 14 and one end of the shaft extends through the head 14 for attachment of a pulley, gear

or any equivalent driving member. The piston 31 is formed with a concentric portion 32 struck from the chamber and shaft center a, adapted to have a close working contact with the interior peripheral wall of the cylindrical pressure chamber 16; and an eccentric portion 33, struck from a center b, spaced from the peripheral walls of the pressure chamber to form therewith a crescent shaped working space 34.

The concentric portion 32 is preferably of considerable extent so as to present a long contact surface to the cylinder walls for minimizing leakage of fluid therealong and to cover both the inlet and outlet ports when passing the same for a purpose hereinafter disclosed. As shown it subtends an angle of approximately ninety degrees.

Means is provided for closing the ends of the cylindrical pressure chamber 16 about the piston 31. This means may be provided either as a part of the casing or as a part of the rotor depending upon the structural disposition of certain related parts as will be obvious from the entire description. Herein it comprises spaced end plates 36 having an interior opening fitting closely about hubs 37 provided on the rotor and secured to the ends of the piston by screws 38 or the like.

According to this invention means is provided to cooperate with the piston to furnish

a separation in the pressure chamber between the inlet and outlet ports. This means is preferably operated positively from the moving rotor and desirably also is arranged to have a close working fit with a portion of the piston 31. This means may comprise an abutment 40 slidably mounted in an oscillatory cylindrical block 41 fitting tightly within a cylindrical bore 42 provided in the casing. A channel 43 is formed in the casing between the chamber 42 and the pressure chamber 16 to accommodate the abutment in its oscillatory movement.

The abutment may be operated from the rotor in various ways. The construction herein shown comprises an eccentric groove 45 formed in each of the rotor end plates 36, which grooves are struck from the center *b*. Eccentric straps 46 fit into these grooves 45 and are formed integral with extension pieces 47 secured to each end of the abutment 40 by screws 48 or the like, the extension 47 being of the same width as the abutment and also fitting within the cylindrical oscillating blocks 41.

Provision is herein made for closing the ends of the connecting channel in which the abutment operates. This is accomplished in part by the outer edges of the rotor end plates 36 but, in addition thereto, packing plates 50 are employed. These packing plates 50 have an arc-shaped surface 51 of the same curvature as and closely engaging the outer periphery of the end plates. They may be secured by screws 52 or the like to the casing at either side of the oscillating block 41 as is most clearly seen in Fig. 3. The plates 50 also serve to retain the block 41 in correct position as well as to prevent leakage past the ends of the same.

The inner face of the abutment 40 is formed on an arc struck from the eccentric center *b*, the radius of the arc being the same as the radius of the eccentric portion 33 of the piston. From this it will be seen that the abutment will closely engage the eccentric portion of the piston at all times during its passage but will stand above the concentric portion 32 of the piston while the same is passing the abutment, thus avoiding wear on the latter. Since the virtual center of connection of the abutment corresponds with the center of the eccentric portion of the piston it will be obvious that the arc face of the abutment will fit upon this eccentric portion throughout its length in all rotated positions of the piston and corresponding oscillated positions of the abutment.

This invention also contemplates the employment of suitable packing upon the abutment and upon the interior surface of the cylindrical pressure chamber for minimizing leakage in the operation of the piston. The packing on the abutment may consist of several longitudinal packing strips 55 set into

recesses 56 cut back from the arc surface of the abutment and these packing strips have projections 57 extending into the grooves 45 of the end plates with the eccentric straps 46 so that they may be held in proper position upon the abutment at all times.

The pressure chamber packing may comprise a plurality of similar strips 58 set into recesses in the casing and provided with end projections 59 overlying the edge of the rotor end plates for fixing the position of the packing strips i. e. to prevent them from falling into the pressure chamber when not engaged by the concentric portion 32 of the piston.

Preferably means is provided on the rotor for removing grit or other solid material from the chamber and this may be accomplished by a small longitudinal groove 35 provided on the piston.

The operation of the pump may be understood by reference to the diagrammatic Figures 7 to 10. In Fig. 7 the trailing end of the concentric portion of the piston is just passing the edge of the slit-like inlet port 17 while the working space filled with fluid is disposed on the opposite side of the cylindrical chamber and fluid is being forced from the outlet port 18. In this view the abutment 40 has been drawn into close engagement with the eccentric surface 33 of the piston. Fig. 8 shows the parts at approximately mid stroke where the abutment forms a tight closure between the inlet port and the outlet port. Fluid is being drawn in at the inlet and discharged at the outlet. Fig. 9 shows the position of parts at the completion of the working stroke. Here the working space 34 is positioned adjacent the inlet port and the piston has completed expulsion of fluid between itself and the abutment through the outlet port. The abutment has not quite begun rising out of contact with the piston. In Fig. 10 the parts are shown during the transition period while the concentric portion of the piston is moving between the outlet and the inlet. The abutment is raised above the surface of the piston but the concentric surface of the piston is of sufficient length, as has already been explained, to close both inlet and outlet ports to prevent the flow of fluid therebetween. This closure is effected from the time the forward edge of the concentric portion of the piston engages the edge 60 adjacent the outlet port until the trailing edge of the concentric portion 32 passes the concentric edge of the casing 61 adjacent the inlet port.

The next position according to these views will be the same as that shown in Fig. 7 where the cycle is begun anew.

Applicant is aware that various changes and modifications may be made within the scope of the appended claims.

What I claim is:

1. In a rotary pump or the like, in combination, a casing comprising an intermediate portion having a cylindrical chamber and circumferentially spaced inlet and outlet ports, and heads at either end having shaft bearings coaxial with the chamber, a rotor comprising a shaft journaled in said bearings, a piston fast on said shaft within said chamber having a portion concentric with the chamber and an eccentric portion defining with the walls of said chamber a working space, and circular end plates secured to the piston closing the ends of said chamber, said end plates having 10 grooves on their inner faces concentric with the eccentric portion of said piston, an abutment disposed between the inlet and outlet ports comprising a blade adapted to cooperate with said piston and end portions fitting in said rotor plate grooves for imparting movement to said abutment, an oscillatory block slidably receiving said abutment, packing plates fixed to said casing bearing along an arc at one edge thereof upon the circumference of said rotor plates and on a face thereof against the ends of said abutment and oscillating block for preventing leakage, longitudinal packing strips on said abutment blade adapted to bear upon the eccentric portion of said piston, and other longitudinal packing strips in the casing about the cylindrical chamber thereof adapted to bear upon the concentric portion of said piston, said abutment packing strips being provided with 20 end projections disposed within the grooves of the rotor end plates, and said casing packing strips being provided with end projections bearing upon the outer surface of said rotor plates for retaining said packing strips in correct position.
2. In a rotary pump or the like in combination, a casing comprising an intermediate portion having a cylindrical chamber and circumferentially spaced inlet and outlet ports, and heads at either end, a piston rotatable in said chamber, said piston having a portion in contact with the chamber walls and a portion eccentric with respect to the chamber and the axis of rotation of the piston, an oscillatable and slidable abutment adapted to operate in engagement with the eccentric portion of said piston, and means operatively connecting said abutment with said piston, said means having an effective center of connection with said abutment coinciding with the center of the eccentric portion of said piston.
3. In a rotary pump or the like in combination, a casing having a cylindrical chamber and spaced inlet and outlet ports opening into the chamber, a rotatable piston operable in said chamber having a portion concentric with and substantially in contact with the peripheral wall of the chamber and an eccentric portion, an abutment associated with
- said piston, and means to cause said abutment to engage said eccentric piston portion throughout its length but to stand clear of said concentric portion while the same is passing the abutment, said concentric portion at 70 such times providing a separation between the inlet and outlet ports on the side on which the abutment is located.
4. In a rotary pump or the like in combination, a casing having a cylindrical chamber, 75 a rotor comprising a piston rotatable in said chamber, end members closing the ends of said chamber about the piston, an oscillating and reciprocating abutment adapted to cooperate with said piston, said casing being so cut away to permit oscillation of the abutment, eccentric means for operating said abutment from said rotor, and means cooperating with the end members of said rotor to seal the ends of the cut away portion of the 85 casing.
5. In a rotary pump or the like in combination, a casing having a cylindrical pressure chamber, a second cylindrical chamber spaced therefrom and a passage connecting said 90 chambers, a piston rotatable in said pressure chamber, an abutment block oscillatable in the second chamber, an oscillatory abutment cooperating with said piston and block extending through said passage, and means to 95 close the ends of said pressure chamber about the piston and the ends of said passage about said abutment.
6. In a rotary pump or the like in combination, a rotatable piston, an oscillatory and reciprocatory abutment cooperating with said piston, and means including an eccentric device for operating said abutment in timed relation with said piston.
7. In a rotary pump or the like in combination, a rotatable piston having a portion concentric with the axis of rotation and a circular portion eccentric to the axis of rotation, an oscillatable and reciprocatable abutment cooperating with said piston, and means including an eccentric device for operating said abutment by movement derived from said piston, said means including a rotatable member having a virtual connecting center with said abutment which coincides with the center of the eccentric portion of said piston.
8. A device as set forth in claim 6 in which said connecting means further includes an eccentric strap secured to the end of said abutment.
9. A device as set forth in claim 6 in which said eccentric device comprises a grooved plate secured to the end of said piston.
10. A device as set forth in claim 6 in which said eccentric device includes a grooved plate secured to the end of said piston and a member having an annular ring fitting in said groove and a portion secured to the end of said abutment.
11. In a rotary pump, a casing having a 130

cylindrical chamber, a flanged rotor disposed in said chamber, and packing strips disposed within the peripheral wall of the chamber and retained in position by engagement with the rotor flanges.

12. In a rotary pump, a pair of spaced rotatable plates having grooves therein, a slideable abutment provided with end extensions disposed within said grooves, and said slideable abutment having a concave bearing surface, and longitudinal strips set into the abutment to face with said concave surface and provided with portions extending into the grooves of the plates to retain said packing strips in correct position.

13. Apparatus of the character described comprising a casing having a cylindrical chamber, a rotatable piston disposed in said chamber and having a longitudinal notch on its periphery for removing grit from the surface of said cylindrical chamber with which said piston is adapted to cooperate.

14. Apparatus of the character described comprising a rotary piston having a concentric portion and an eccentric portion, a slideable abutment and means to raise said abutment clear of the concentric piston portion but allowing it to engage the eccentric portion.

15. In testimony whereof, I have signed my name to this specification this 19th day of December, 1927.

CALVIN M. BOLSTER.
